James W. Augustine

Inventor

By Clarence A. O'Brien Attorney

UNITED STATES PATENT OFFICE

JAMES WILLIAM ANSTINE, OF YORK, PENNSYLVANIA

ADJUSTABLE LOCK KEEPER

Application filed March 11, 1931, Serial No. 521,826. Renewed June 20, 1932.

This invention relates to an adjustable keeper for a lock or latch, the general object of the invention being to provide means whereby the keeper member can be adjusted both in a transverse direction and in a longitudinal direction to compensate for sagging of the door or other carrier, and to enable the keeper member to be adjusted so that the bolt of the lock or latch will properly engage the same.

This invention also consists in certain other features of construction and in the combination and arrangement of the several parts, to be hereinafter fully described, illustrated in the accompanying drawing and specifically pointed out in the appended claim.

In describing the invention in detail, reference will be had to the accompanying drawing wherein like characters denote like or corresponding parts throughout the several views, and in which:—

Figure 1 is an elevation showing part of a door and a part of a frame with the improved keeper member on the frame for engaging the bolt of the latch on the door.

Fig. 2 is an edge view looking toward the keeper member.

Fig. 3 is a section on the line 3—3 of Fig. 1. Fig. 4 is a section on the line 4—4 of Fig. 1.

In these views, the letter A indicates a door or other barrier and the letter B a part of the frame thereof, the door carrying a lock C, the bolt of which is adapted to engage a keeper member 1 on the frame, in the usual manner. An angle plate 2 is fastened to an edge of the frame B by the screws 3 and covers a groove or recess 4 in said frame. The plate is formed with a longitudinal slot 5. A second angle plate 6 is supported for vertical movement on the plate 2 through means of the screw 7 carried by the plate 6, passing through the slot 5 in the plate 2 and passing into threaded holes in a plate 8 located in the recess 4 and engaging the inner side of the limb of the plate 2.

Thus by loosening the screws 7, the plate 6 can be adjusted vertically on the plate 2 and thereby tightening the screws 7, the plate 6 will be held in adjusted position on the plate 2.

This plate 6 is formed with a horizontal rib 9 on its outer face which is of dove-tail shape and the inner face of the member 1 is formed with a dove-tail groove 10 for receiving said rib, so that said keeper member 1 is supported for horizontal sliding movement on the plate 6.

A horizontal slot 11 is formed on each end of the keeper member 1 and a screw 12 passes through each slot and is threaded into the plate 6, so that by loosening the screws 12, the keeper member 1 can be adjusted horizontally toward and away from the lock C and then by tightening the screws 12, the keeper member is fastened in adjusted position on the plate 6.

Thus I have provided simple means for adjusting the keeper both vertically and horizontally so as to insure the bolt of the lock properly engaging the keeper recess 13 in the keeper member.

It is thought from the foregoing description that the advantages and novel features of the invention will be readily apparent.

It is to be understood that changes may be made in the construction and in the combination and arrangement of the several parts, provided that such changes fall within the scope of the appended claim.

Having thus described my invention, what I claim as new is:—

In combination with a keeper member for a lock or latch bolt and a frame member having an elongated recess in one face thereof, an angle-shaped plate recessed in the frame member and having one part covering the recess and its other part engaging an edge of the frame member, said plate having a slot in communication with the recess, a second angle-shaped plate resting on the first

plate, screws passing through the second plate and through the slot in the first plate, a bar located in the recess and contacting with the slotted part of the first plate and receiving the ends of the screws, said second plate having a horizontal rib on its outer face of dovetailed shape, and said keeper member having a horizontal groove of dove-tail shape for receiving the rib, flanges on the ends of the keeper member and horizontal slots therein and screws passing through the slots into the second plate.

In testimony whereof I affix my signature.

JAMES WILLIAM ANSTINE.
